UNITED STATES PATENT OFFICE.

LEWIS M. ELLISON, OF CHICAGO, ILLINOIS.

GAS-COLLECTOR.

1,128,669.

Specification of Letters Patent. Patented Feb. 16, 1915.

Application filed May 11, 1914. Serial No. 837,855.

To all whom it may concern:

Be it known, that I, LEWIS M. ELLISON, a citizen of the United States, and resident of Chicago, county of Cook, and State of Illinois, have invented certain new and useful Improvements in Gas-Controllers, of which the following is a specification, and which are illustrated in the accompanying drawings, forming a part thereof.

10 The invention relates to devices adapted to collect gases in measured quantities for the purpose of analysis, as for the collection of gases from a furnace for the purpose of determining by their analysis the efficiency 15 of operation. For this particular service it is desirable to draw from the furnace or its flues and store gas at a uniform rate for a definite period of time. This is sometimes accomplished, as in the present instance, by 20 the use of a displacement tank which being filled with water is connected with the flue or chamber from which the gas is to be taken and the water is then drawn off from the tank at a uniform rate, the gas taking 25 its place. In such devices lack of uniformity in the rate at which the gas is stored occurs because there is a variation in the flow of the water from the tank due to the decreasing head, and the principal object 30 of this invention is to provide for a uniform rate of storage within the collecting chamber notwithstanding this variation in the rate of the water discharge.

The invention has for a further object the 35 general improvement of devices of this character.

In carrying out the invention the apparatus is provided with two gas receiving chambers, uniformly but inversely varying in 40 horizontal cross sectional area from top to bottom, both chambers being adapted to be filled with water and having a common outlet therefor; both being connected with the source of gas supplied and the chamber having 45 its smaller end uppermost and being provided with an eduction duct to permit the withdrawal of gas therefrom. By this relative arrangement of tanks the ratio of the discharge of the water from the compartment having its smaller end uppermost 50 will gradually increase relatively to the discharge from the other chamber as the level of the water is lowered, and, as the rate of discharge of the water will decrease with 55 its head, the rate of displacement in the chamber having its smaller end uppermost,

may be made constant by a proper proportioning of the two chambers. The apparatus is also provided with means for preventing the stratification of the gases within 60 the collecting chamber and with the liquid seal for the gas eduction duct.

The accompanying drawing shows a vertical central section of the device, showing one embodiment of the invention.

As here represented the displacement tank comprises a single shell 10, the body portion of which is of uniform horizontal cross sectional area, subdivided into two chambers 11, 12, by means of a downwardly tapering annular wall 13, depending from the top wall 14 of the shell. Below the shell 10 and open to both of its chambers is a sediment chamber 15. A drain duct 16 leads from the bottom of the sediment chamber, its lower end being constructed, as shown at 17, to provide for a slow discharge or drip of the water. This duct preferably discharges into a chamber 18 provided with an eduction nipple 19 located at a greater 70 elevation than the drip port 17. The nipple 19 discharges into a waste pipe 20. A valve 21 is provided for closing the drip port 17. The duct 16 is continued upwardly as a tube which terminates within the lower end of 75 the chamber 12, thereby insuring a liquid seal between the two chambers of the tank while any water remains therein.

A nipple 22 attached to the top 14 of the tank is adapted to be connected to the source 90 from which the gas is to be drawn by suitable piping. The nipple being provided with a duct 23 delivering to the tank compartment 11 and also having branch 24 delivering to the tank compartment 12. A 95 liquid gage 25 is provided for indicating the level of the liquid in the tank and may be of the ordinary glass tube type having its lower end connected with the sediment chamber 15 and its upper end connected 100 with the duct 23.

A pipe 26 leads from within the tank chamber 11 through a sealing chamber 27 within which it may reciprocate, the chamber 27 being filled with a liquid to prevent 105 the entrance of air. The upper end of the tube 26 terminates within a chamber 28 from which leads a nipple 29 the inner end of which extends below the upper end of the pipe 26. The chamber 28 being partially 110 filled with liquid so that normally the inner end of the nipple 29 is submerged, a liquid

seal is provided to prevent the escape of gas. A hand controlled plunger 30 reciprocating within a cylinder 31 projecting laterally from the lower portion of the chamber 28 provides means for lowering the level of the liquid within that chamber to permit the escape of the gas through the nipple 29.

The pipe 26 is reciprocable in order that its lower end will be normally submerged in the liquid in the tank, but may be drawn upward to permit the escape of gas and also to provide for the withdrawal of gas, if desired, from different elevations within the tank for the purpose of determining whether stratification of the gas within the tank has been broken up. Preferably a dasher 32 is fixed to the lower end of the pipe 26. By the proper manipulation of the pipe 26 this dasher may be raised and lowered and will effectually break up the stratification of the gases within the chamber 11 and render them uniform throughout the entire mass.

For the purpose of filling the tank with water, a pipe 33 is provided, the upper end of which is as high as the top of the tank. This pipe delivers to an air separating trap 34 having a vent 35, and to a duct 36 delivering to the tank so as not to disturb the sediment which may have accumulated within the chamber 15. Preferably, as shown, the duct 36 rises through the chamber 15, and to provide for the escape into this chamber of any sediment which may fall into the open end of the duct, a small port is located near its lower end. A drain pipe 37 is provided for carrying away water which may overflow from the filling pipe 33.

The chamber 12 when located as shown within the chamber 11, the outer walls of the latter being vertical, the horizontal cross sectional area of the chamber 11, increases downwardly from its upper end. The chambers 11, 12 being connected at their lower ends, the level of the liquid within them is of course the same. The rate at which this level is lowered by the dripping of the water from the duct 17 will gradually decrease as the level is lowered and the head thereby decreased. As the relative horizontal cross sectional areas of the chambers 11 and 12 inversely vary with the altitude, it follows that as the level of the water is lowered, a substantially increasing proportion of the gas drawn from the duct 23 is delivered to the chamber 11. By a proper proportioning of the chambers 11 and 12, this variation in the distribution of the gases between the two chambers will exactly correspond to the variation in the rate of discharge of the water and the rate at which the gas is delivered to the chamber 11 will remain constant.

If it be desired to ascertain the average

efficiency of a furnace for a given period, say eight hours, the tank is filled with water, the surface of the water being preferably covered by a film of non absorbing oil. The duct 23 is connected with the furnace flue and the port 17 is opened. As the water is drained from the tank, furnace gas takes its place in both chambers 11, 12. As the rate of discharge of the water diminishes by reason of the lowering of its level, the rate of the withdrawal of the gases from the furnace correspondingly decreases. Nevertheless owing to the decreasing cross-sectional area of the chamber 12 and the increasing cross-sectional area of the chamber 11, toward the bottom of the tank, the rate of delivery of the gas to the latter chamber remains constant. Before withdrawing any of the gas from the chamber 11 for the purpose of analysis, the dasher 32 is preferably given a few strokes for the purpose of insuring a complete admixture of the gases and their analysis will, therefore, indicate the average efficiency of the furnace during the entire period covered by the test.

While the gas receiving compartments 11, 12 are shown as both being within the shell 10, this is not of the essence of the invention, it being important only that their relative proportions should be such that there is a proper increase and decrease, respectively, in the cross sectional areas of the two chambers from their upper ends downwardly.

I claim as my invention,

1. In a gas collector, in combination, a tank having a drip nipple and a body of uniform horizontal cross-sectional area, an open bottomed downwardly tapering compartment within the tank, an induction duct leading to the upper ends of both compartments of the tank, and an eduction tube leading from the tank outside of the named tapering compartment.

2. An upright tank having a drip nipple, and a body of uniform horizontal cross-sectional area and having a partition extending downwardly from its top and being inclined from the vertical, an induction duct delivering to the upper ends of both compartments, and an eduction tube delivering from the compartment which increases in cross sectional area from its upper end.

3. A tank having a body of uniform horizontal cross-sectional area and being divided into two compartments correspondingly inversely varying in horizontal cross-sectional area from top to bottom, a drip nipple draining from both compartments, an induction duct leading to both compartments and an eduction tube leading from the compartment the greatest area of which is at its lower end.

4. A pair of chambers correspondingly inversely vertically tapered, a drip nipple common to both chambers, an induction

duct leading to both chambers, and an eduction tube leading from the chamber having its smaller end uppermost.

5. An upright tank having its body of uniform diameter, a downwardly tapering chamber within the tank and being open to the chamber of the tank at its lower end, a drip nipple at the bottom of the tank, inlet ports at the top of the tank chamber and 10 tapering chamber and an eduction tube for the tank chamber.

6. An upright tank having its body of uniform diameter, a downwardly tapering chamber within the tank and being open to the chamber of the tank at its lower end, a drip nipple at the bottom of the tank, inlet ports at the top of the tank chamber and 15 tapering chamber and means for drawing off the contents of the tank at varying elevations.

20 7. An upright tank having its body of

uniform diameter, a downwardly tapering chamber within the tank and being open to the chamber of the tank at its lower end, a drip nipple at the bottom of the tank, inlet ports at the top of the tank chamber and 25 tapering chamber and an eduction tube reciprocable through the top wall of the tank.

8. An upright tank having its body of uniform diameter, a downwardly tapering 30 chamber within the tank and being open to the chamber of the tank at its lower end, a drip nipple at the bottom of the tank, inlet ports at the top of the tank chamber and tapering chamber and an eduction tube reciprocable through the top wall of the tank, 35 and a dasher carried by the tube.

LEWIS M. ELLISON.
